DESIGN FOR AN ANTITHEFT DEVICE FOR TANKS CONTAINING LIQUID

Alcide E. Mathey, Boston, Mass., assignor to Scully Signal Co., East Cambridge, Mass., a corporation of Massachusetts

Application September 17, 1941, Serial No. 103,393

Term of patent 14 years

To all whom it may concern:

Be it known that I, Alcide E. Mathey, a citizen of the United States, residing at Boston, in the county of Suffolk, State of Massachusetts, have invented a new, original, and ornamental Design for an Antitheft Device for Tanks Containing Liquid, of which the following is a specification, reference being had to the accompanying drawing, forming part thereof.

Fig. 1 is a side perspective view of an anti-theft device for tanks containing liquid, showing my new design;

Fig. 2 is a top plan view thereof; and
Fig. 3 is a side elevational view thereof.

I claim:

The ornamental design for an antitheft device for tanks containing liquid, as shown.

ALCIDE E. MATHEY.
